EMBOSSSED LEATHER FOR HAND BAGS AND OTHER FANCY LEATHER GOODS.

No D 16,486.

Patented Jan. 19, 1886.

UNITED STATES PATENT OFFICE.

JOHN MEHL, SR., OF HOBOKEN, NEW JERSEY.

DESIGN FOR EMBOSSED LEATHER FOR HAND-BAGS AND OTHER FANCY LEATHER GOODS.

SPECIFICATION forming part of Design No. 16,486, dated January 19, 1886.

Application filed December 19, 1885. Serial No. 186,234. Term of patent 7 years.

To all whom it may concern:

Be it known that I, JOHN MEHL, Sr., of Hoboken, in the county of Hudson and State of New Jersey, have invented and produced a new and original Design for Embossed Leather for Hand - Bags and other Fancy Leather Goods, of which the following is a full, clear, and exact description.

Reference is to be had to the accompanying photograph, forming a part of this specification, and which is a plan view of my design.

The leading feature of my design consists in the representation in relief of various human figures in various attitudes, and represented as mounted on roller-skates and clothed in the costumes of various nationalities. The figures are represented singly and in groups, and as separated by vines and flowers.

I claim—

The design for embossed leather for hand-bags and fancy leather goods herein shown and described, the same consisting of the representation in relief of various human figures, singly and in groups and in various attitudes, clothed in the costumes of various nationalities, mounted upon roller-skates, and separated by vines and flowers.

JOHN MEHL, SR.
